UNITED STATES PATENT OFFICE.

MICHAEL A. DROITCOUR, OF MAYWOOD, ILLINOIS.

SHEET-FEEDER.

1,146,929.

Specification of Letters Patent. Patented July 20, 1915.

Application filed September 13, 1913. Serial No. 789,591.

To all whom it may concern:

Be it known that I, MICHAEL A. DROITCOUR, citizen of the United States, residing at Maywood, in the county of Cook and State of Illinois, have invented a certain new and useful Improvement in Sheet-Feeders, of which the following is a full, clear, concise, and exact description, reference being had to the accompanying drawings, forming a part of this specification.

My invention relates to sheet feeding machines and has a number of objects and advantages in view.

In accordance with one feature of my invention the sheet feeder includes a suction shoe, and a reciprocable support for the shoe upon which it is pivotally mounted. There is also preferably included a connection anchored at one end exteriorly of the shoe and at the other end attached to the shoe and a spring for maintaining the connection taut.

In accordance with another feature of the invention an abutment is provided with which sheets lifted by the suction shoe are brought into striking engagement to dislodge the sheets that are not to be lifted.

In accordance with another feature of the invention I provide means for elevating sheet portions of sheets that are to be fed from a pile of sheets, a finger for resting upon the pile of sheets between the lifted sheet and the remaining sheets, and mechanism for moving such finger inwardly over said pile of sheets and downwardly into contact therewith after the lifting operation. This finger is also preferably lifted and withdrawn outwardly preparatory to another sheet lifting operation.

In accordance with another feature of the invention I employ a suction wheel whose periphery is perforated to enable air to be drawn inwardly through the wheel, the periphery being flattened where perforated so that the sheets may have flat engagement with the wheel or the outsetting curvature is otherwise removed where the wheel is perforated though it is preferred to flatten the periphery to enable the sheets to have more extended engagement with the wheel.

In accordance with another feature of the invention the periphery has recesses surrounding the perforations therein for holding the heavier sheets and within which recesses portions of lighter sheets may be drawn to seal the perforations thereby to enable the suction wheel to operate upon lighter sheets.

In accordance with another feature of the invention a substantially non-rotating suction shoe is located within the suction wheel, this shoe being movable radially of the wheel to maintain engagement with the inner portion of the wheel rim, a spring being preferably employed for maintaining the shoe and wheel in engagement.

In accordance with another feature of the invention I provide a mechanical sheet lifter for lifting the bottom sheets to prepare them for the feeding operation when the pile of sheets has been sufficiently reduced to permit of the operation of this mechanical sheet lifter.

My invention has a number of other objects and advantages in view which are preferably attained by the embodiment of the invention herein disclosed but to which embodiment the various features are not to be limited.

The invention will be fully set forth by reference to the accompanying drawings and in the appended claims.

In the drawings Figure 1 is a side view partially in section illustrating the machine of the invention; Fig. 2 is a plan view of the equipment illustrated in Fig. 1, some parts being omitted for the sake of clearness; Fig. 3 is a sectional elevation on line 3 3 of Fig. 1; Fig. 4 is a sectional elevation on line 4 4 of Fig. 2; Fig. 5 is a sectional elevation on line 5 5 of Fig. 2; Fig. 6 is a view in transverse section illustrating a side guide; Fig. 7 is a sectional view on line 7 7 of Fig. 2; Fig. 8 is a sectional view on line 8 8 of Fig. 9; Fig. 9 is a view partially in elevation and partially in section on line 9 9 of Fig. 7 of a portion of the structure illustrated in Fig. 7, the part which is in section being taken on line 9 9 of Fig. 7; Fig. 10 is a view on a larger scale of a part of the structure as it appears in Fig. 1; Fig. 11 is a plan view of structural portions illustrated in Fig. 10 on line 11 11; Fig. 12 is a view on a larger scale of a part of the structure as it appears in Fig. 2; Fig. 13 is a view on line 13 13 of Fig. 12; Fig. 14 is a detail in section of a part of the structure illustrated in Fig. 13; Fig. 15 is a sectional view on line 15 15 of Fig. 13; and Fig. 16 is a view on line 16 16 of Fig. 12.

Like parts are indicated by similar characters of reference throughout the different figures.

The sheet feeding machine of my invention is adapted to feed sheets for a variety of purposes such, for example, as to printing

presses, perforating machines and folding machines, and the invention is not therefore to be limited to any use to which it may be put. In the embodiment of the invention 5 herein shown the sheets are fed by means of my machine to a perforating machine indicated at 1 and, as such perforating machine forms no part of my invention, the same will not be described.

10 The sheets, such as sheets of paper, are piled at 2 upon a supporting board or platform 3 resting at its side margins upon the angle irons 4 carried upon symmetrically positioned stretches of vertically disposed 15 endless sprocket chains 5 which pass over sprocket wheels 6 at the upper limits of their travel and over sprocket wheels 7 at the lower limits of their travel, the latter sprocket wheels being driven by an intermittently driven shaft 8 through the intermediation of worm shafts 9 and worm wheels 10. The support 3 is to be elevated from time to time to compensate for the reduction in the thickness of the pile as the 20 sheets are fed from the pile. In the instrumentalities which enter into the step by step upward adjustment of the paper support 3 there is included a cam support 11 which is rotated at a uniform speed, this cam support 25 11 carrying a cam roller 12 concentric with the axis of rotation of the cam support 11 and working back and forth within the elongated slot 13 of a lever 14 fulcrumed at 15. A link 16 connects an intermediate 30 portion of the lever 14 (Figs. 1, 2, 10 and 11) with one end of the bell crank 17 upon whose other end a pawl carrier 18 is pivotally mounted, a spring 19 pressing this pawl carrier upwardly. The pawl 20 is pivotally mounted upon the pawl carrier, the tail of the pawl 20 being upwardly pressed by a spring 21 whereby the pawl is pressed downwardly, the extent to which the pawl 20 may be downwardly pressed by the spring 40 21 being limited by engagement of the tail with the shaft 23 upon which the pawl support 18 is pivotally mounted. The spring 19 is, when unopposed, sufficiently strong not only to hold the pawl support 18 in that 45 position in which the pawl 20 will be normally out of engagement with a ratchet wheel 24, but is also sufficiently strong to support a normally idle depressor 25 normally free to oscillate about its pivotal 50 mounting 26. This depressor carries a foot 27 near its outer end, this foot being normally out of the alinement with a depressing finger 28 constituting one branch of a bell crank whose companion branch is articulated to a link 29 having its upper end connected with the outer end of a lever 30 fixed with respect to a shaft 31 (see also Figs. 3 and 7). Another lever 32 is also fixed with respect to the shaft 31, this lever 55 32 being connected by a link 33 with a lever 34 (see particularly Fig. 3) that is fixed upon a shaft 35. A miter gear 36 is splined upon the shaft 35 and is in mesh with a companion miter gear 37 upon which a finger 38 is fixedly secured. The lower and 60 free end of this finger rests upon the paper at 2, being maintained in engagement with the paper by means of a spring 39 secured to the upper end of a lever 40 fixed upon the shaft 35. As the pile of paper is reduced 65 the spring 39 turns the rod 35 to the extent permitted by the finger 38. A cam 41 upon constantly driven shaft 42 intermittently engages a cam roller 43 upon the upper end of a cam element 44 fixed upon the shaft 35 whereby the finger 38 is raised each time a sheet is to be fed from the pile, the cam 41 thereafter operating to permit 70 the spring 39 to reapply the finger 38 to the paper to hold the sheet immediately below the sheet being fed so as to maintain it upon its pile until the time for feeding it has arrived. When the pile has been so far reduced in height to require its bodily elevation to enable the feeding of the sheets 75 therefrom properly to continue, the spring 39 is permitted by the finger 38 so far to turn the shaft 35 that this shaft will, through the intermediation of connections intervening between it and the finger 28, bring this 80 finger into alinement with the foot 27 so as to hold the outer end of the depressor 25 in a lowered position, in which position the lower curved surface of the depressor 25 will engage and depress the pawl carrier 18 85 so as to bring the pawl 20 into engagement with the ratchet 24 to turn the same say, the space of five teeth. As the ratchet wheel 24 is fixed upon the shaft 8 the worms 9 upon the ends of the shaft 8 will turn the 90 worm wheels 10 in a direction that will elevate the platform 3 to restore the upper surface of the pile of paper to its initial level. When the platform 3 has thus been 95 elevated the finger 38 operates, in the manner now obvious, to prevent the finger 28 from coming into alinement with the foot 27, such alinement being avoided until the pile has again been reduced to that point 100 where it should again be elevated. The finger 28 is thus kept in constant oscillation through the direct agency of the cam elements 41 and 43, the extent of this oscillation being determined by the finger 38 whereby such oscillation is not effective for the 105 purpose of raising the pile of paper until the range of oscillation has been so increased as to bring the elements 27 and 28 into alinement. I thus employ constantly moving parts which are normally ineffective but 110 which are readily made effective when the time arrives for raising the pile, the entire construction being such that a delicate and sensitive control of the elevation of the 115 paper is secured. In practice I have been 120

125 130

able to secure reelevation of the pile of paper each time it has been decreased one-sixty-fourth of an inch in height. When all of the paper has been fed from the platform 3 further elevation of the platform is prevented owing to the fact that the finger 38 can no longer descend sufficiently far with respect to the platform 3 whereby the finger 28 cannot thereafter engage the foot 27 for the purpose of elevating the platform 3. The attendants will thereupon remove the support or platform 3 from which the pile of paper has been fed and will place a new loaded support 3 upon another pair of angle irons 4.

The mechanism for feeding the sheets from the pile 2 includes a suction producer 45 to the intake side of which a pipe 46 extends. This pipe is provided with bifurcations 47, 48 alternately through which air is drawn to the main branch 46 according to the position of the two-way valve 49. The element 11 has its periphery so shaped as to constitute a cam that works in cooperation with a cam roller 50 mounted upon a lever 51 which is provided with a forked end which straddles the shaft 42 upon which the element 11 is mounted. The lever 51 is connected at its upper end with an arm 52 fixed upon a shaft 53 and to which shaft another arm 54 is rigidly secured, the arm 54 being connected by a link 55 with a valve lever 56 belonging to the valve 49. The cam 11 so operates upon the cam roller 50 as first to establish a passage for inflowing air through the pipe branch 47 and the flexible continuations 56¹ thereof and thereafter cut off the flow of incoming air at 56¹ and establish a passage for inflowing air through the flexible pipe portion 48.

Referring now more particularly to Figs. 2, 12, 13, 14, and 15, the flexible extensions 56¹ extend to suction shoes 57, these shoes having each a rigid shank 58 pivotally mounted at 59 at a center which is slightly to the left (as seen in Figs. 13 and 14) of the center of the lower arc of the shoe. The shaft 42 is provided with a cam 60 having a cam groove receiving a cam pin 61 upon the upper end of an arm 62 rigidly secured upon a shaft 63. A miter gear 64 is splined upon shaft 63 and is in mesh with a miter gear 65 rigidly mounted upon a shaft 66. Miter gears 67 are splined upon the shaft 66 and are in mesh with miter gear 68. An arm 69 is rigid with respect to each gear 68. By means of the cam 60 and intervening parts, the gears 68 are oscillated to oscillate the arms 69. The arms 69 engage grooved posts 70 projecting upwardly from slides 71 mounted to reciprocate upon guide rods 72. Strips or connections 73 are each stationarily anchored at 74 at one end and are attached at the other end to the corresponding shoe 57 at 75. Thus when the slides 71 are

moved rearwardly, or to the right as viewed in Figs. 12 and 13, the shoes 57 are rocked in clockwise direction against the force of spring 76 which serves to restore the shoes to the positions illustrated when the arms 69 are returned to the positions illustrated, the spring 76 serving to maintain the strips 73 taut. When the shoes 57 have been rotated in a clockwise direction the mouths 77 thereof are presented to the top sheet, at which time air is being drawn through the shoes whereby the top sheet is drawn into contact with the shoes so that when the shoes are returned to the positions illustrated in Figs. 12 and 13 the upper sheet of paper is lifted at its rear margin. In order to have but one sheet lifted I provide an abutment 78 at the right hand end of each shoe which brings the periphery of the shoe in position to be engaged by the lifted sheet and that operates to dislodge any lower sheet or sheets which may happen to be lifted with the uppermost sheet, the abutment projecting downwardly below the sheet engaging face of the shoe for this purpose. The extent to which the abutment 78 projects below the shoe is determined by an adjusting screw 79 operating against the shoe to offset the resilience of the abutment, which is preferably made of strip spring metal, the resilience of the spring 78 operating to bring the element 78 toward the shoe. The abutment 78 performs its function before the return movement of its corresponding shoe in a counter-clockwise direction is commenced. Now that the sheet has been lifted at its rear end it is pulled off its pile by effort applied at its forward end by mechanism hereinafter to be described and in order to prevent other sheets from being pulled off the pile with the top sheet I associate with each shoe 57 a depressing finger 80, mounted to move diagonally of the paper, whose forward end is adapted to rest upon the sheet of paper immediately below that being fed from the pile and which is pivoted near its rear end upon the bracket 81 projecting from a support 82 adapted to slide back and forth upon the rods 83 projecting rearwardly from a stationary support 84. A spring 85 is associated with each finger 80 and is anchored at one end to the associate arm 69 and at the other end to a stud 86. The stud 86 is carried by an arm 87 fixed upon a shaft 88 which is journaled in a bracket 89 carried upon the normally stationary support 84. An arm 90 is fixed with respect to the arm 87 and carries a stud 91. The finger 80 is provided with upwardly projecting tail pieces 92 interposed between and in engagement with the free end of a coil spring 93 and the stud 91, the coil spring 93 being anchored upon the support 84. When the arms 69 are being moved in a counter-clockwise direction these arms 130

pull upon the springs 85 and the studs 86 to move the studs 91 against the tail pieces 92 and against the force of the springs 93 to move the supports 82 inwardly upon the 5 guide rods 83. During this movement of the supports 82 the fingers 80 are horizontal and elevated from the paper during which time the top sheet is being lifted by the 10 shoes 57. When the top sheet has been nearly lifted at its rear the fingers 80 are lowered owing to the arrest of the sliding 15 supports 82 by the normally stationary supports 84 whereby the fingers 80 are located into engagement with the sheet below the lifted sheet, the springs 85 operating yieldingly to maintain such engagement. When 20 the arms 69 move in a clockwise direction the tension upon the springs 85 is relieved sufficiently to permit the springs 93 to bring the fingers 80 to a horizontal position in which they are relieved from engagement 25 with the pile of paper, the springs 93 then operating to remove the sliding supports 82 rearwardly to a position determined by the stops 94, this elevation and withdrawal of 30 the fingers 80 diagonally of the paper being for the purpose of enabling the shoes 57 to pick up the next and now the topmost sheet of the pile. It will be observed that the inward movement of the fingers 80 is completed 35 before their downward movement is finished so that the fingers do not push the paper forwardly. Preferably the forward and downturned ends of the fingers 80 constantly overlie the pile of paper irrespective 40 of the positions that such fingers may occupy. It should be said in passing that the center of the lower periphery of each shoe 45 57 is moved to the right of the associate pivot 59 for the purpose of maintaining the corresponding belt 73 sufficiently clear of the paper to permit of other operations later to be described. The supports 84 are, as hitherto stated, normally stationary but are 50 adjustable toward and from each other to adapt the mechanism they support to different widths of sheets. To this end the shafts 66 are in splined connection with the gears 67, the shaft 66 being in free sliding unsplined connection with the supports 84. The shaft 66 is, in its supporting relation to the supports 84, supplemented by a 55 slide guide 95. The supports 84 are adjusted by hand upon the rods 66, 95, the adjustment of these supports being secured by set screws 96. Now that the sheet has been 60 lifted at its rear margin it is to be drawn off the pile at its forward margin, a blast of air passing through the centrally disposed pipe 97 facing the front of the pile of sheets serving there to fluff the sheets to bring the top sheet within range of suction wheels 98 whose interiors are in communication with the suction pipe 48 common thereto and 65 through which wheels 98 and suction pipe

48 air is drawn after the rear margin of the sheet to be fed has been lifted and as suction through the pipes 56 ceases. The suction wheels 98 constantly turn in clockwise directions by means of gearing 99 (which 70 may be the initial power driven elements to operate the entire machine) and a shaft 100 upon which the suction wheels are mounted. The peripheries of the suction wheels are recessed or inset at regular intervals as indicated at 101, the inner portions of the suction wheel peripheries indicated at 101 being provided with apertures 102. The lighter sheets of paper are adapted to be drawn in, where they cover the recesses 101, 75 so as to cover the openings 102. The heavier sheets of paper however will not thus be drawn in to cover the openings 102. Thus the suction area afforded at 102 for the lighter sheets of paper is less than the suction area afforded by the entire recesses 101 for the heavier sheets of paper whereby the attraction for the lighter and heavier sheets of paper is automatically adjusted. The peripheries of the suction wheels 98 are 80 flattened or otherwise relieved of outsetting curvature upon the portions thereof surrounding the recesses 101 so as to have more extended engagement with the paper that is to be fed, considering paper that 85 would be too heavy to snugly engage the outwardly curved portion, instead of opposing curved surfaces to the paper which are defective particularly when heavier paper is to be fed. The suction wheels are 90 provided with the suction shoes 103 which are mechanically and pneumatically coupled by a pipe 104 into which the pipe 48 extends. These suction shoes loosely surround the shaft 100 so as to be movable 95 radially of the wheels thereby to maintain contact with the inner surfaces of the wheel rims and are pressed downwardly by a spring 104¹ and the shoes are prevented 100 from oscillating by the holding structure 105 illustrated at 105. The spring 104¹ operates yieldingly to maintain the lower and peripheral surfaces of the suction shoes in 110 engagement with the cylindrical interiors of the suction wheels, the spaces 106 within 115 the suction shoes directly overlying the places where the paper is to be engaged for the purpose of being withdrawn from its pile. The suction shoes are extended laterally thereof fore and aft so as to have proper 120 engagement with the interiors of the suction wheels, but in order to prevent the suction from being maintained beyond the desired movement of the suction wheels the 125 suction shoes are provided with recesses 107 in communication with the external air. As the suction wheels rotate in their uniform clockwise direction the recesses 101 and the openings 102 are successively brought into 130 communication with the portions 106 of the

suction shoes so that the uppermost sheet of paper is drawn from the pile and is passed over the driven conveyer rollers 108 which convey the paper to the machine 1 that is to operate thereupon.

In order properly to direct air from the pipe 97 to the pile where it is to be picked up by the suction wheel, the pipe would better have its outlet end in line with the upper portions of the peripheries of the rollers 108 to which end the pipe is inturned as indicated in Fig. 7 and is received within a groove 109 in the roller to which such pipe is adjacent. By this disposition of the pipe 97 the blast of air therethrough is substantially parallel with the sheets thereby to get the best spreading action. The bracket 110 upon which miter gear 37 is mounted carries a support 111 for spring fingers 112 which press downwardly upon the pile with slight pressure, sufficiently to prevent the air blast through the pipe 97 from at any time shifting the general position of the top sheets of paper. The part of the device 112 that engages the pile of paper is blunt so as not to penetrate the paper. While the spring fingers 112 are in constant engagement with the paper the finger 38 which presses more heavily upon the paper should be removed from engagement therewith when the top sheet is being fed forwardly, a result which is effected by the proper interrelated cam elements 41 and 43. The operations are so governed that the finger 38 is restored to engagement with the paper just before the fingers 80 break their engagement with the paper while the top sheet is still being pulled from the pile by the suction wheels so that no more than one sheet will be fed. The pawl 20 is moved forward only when the finger 38 is in engagement with the paper, and of course is ineffective until the finger 38 has been brought into alignment with the foot 27 in the manner previously described.

In order to enable me to feed all the sheets from the pile of paper a spring or springs 113 are mounted upon the board 3 at the forward end thereof, this spring being normally depressed to the level of the board by the weight of the pile but when the pile is sufficiently reduced to number but a few sheets the lower sheets of paper are well elevated by the forward end of the spring 113 properly to bring such sheets of paper, owing to the influence of the air blast issuing from the pipe 97, within operating range of the wheels, a result which is obtained without the necessity of a special elevation of the board 3. The normal level of the upper sheet of paper may be determined by shifting the foot 27 back and forth as by means of an adjusting device 114.

A pair of racks 115 are provided for cooperation with the hand operating gearing

116, operated by hand wheel 117 for the purpose of moving the carriers 66 and 95 longitudinally of the machine to adapt the supports 84 and the parts carried thereby to differing lengths of paper, the elements 66 and 95 being connected with carriages 118 upon which the hand operated gearing 116 is mounted, the gear wheel 116 being provided upon a common shaft 119 which passes through the quill shaft 95.

One longitudinal edge portion of each singly fed sheet of paper is passed between the top and bottom portions of a guide 120 whose vertical wall 121 defines the alignment of the paper with respect to the machine 1 which is to operate thereupon, the paper that is being directed through this guide being indicated at 122, Figs. 4 and 6. The entire guide structure 120, 121 is above the rollers 108 whereby such guide may readily be adjusted longitudinally of the rollers 108 and laterally of the machine, provision for such adjustment being illustrated in Figs. 2 and 4 where I have illustrated the guide 121 as depending from sleeves 123 movable transversely of the machine upon frame rods 124, these frame rods constituting a part of the frame in which the rollers 108 are journaled. Referring particularly to Fig. 2, the sleeves 123 are connected by means of frame pieces 125 with an additional sleeve 126 movable transversely of the machine upon one of the rods 124. The rollers 108 are driven in counterclockwise directions so as to convey the sheets to the machine 1 that is to operate thereupon and in order to maintain the sheets in proper engagement with the rollers 108, air is conveyed from the discharge side of the air pump 45 to the wind box 127 located adjacent the guide 120, this wind box being provided with apertures indicated by small dotted circles in Fig. 2 through which air issues under pressure downwardly upon the sheet of paper 122 to maintain the same in proper tractive engagement with the feeding rollers 108. By directing the air downwardly upon the sheet being fed this air will spread and increase the area which is influenced thereby as compared with the areas of the apertures through which the air issues. The wind box 127 is adjustably mounted upon the insetting brackets 128 whereby the wind box may be adjusted transversely of the machine.

A brush 129 is disposed upon the side of the machine opposite that upon which the guide 121 is disposed, a part of the brush bearing upon that edge of the paper opposite to that which is received by said guide 125 and another part of the brush bearing upon the roller disposed beneath the brush whereby the brush operates as a guide complementary to the guide 121 to maintain the proper direction of travel of the sheet. This

brush is adjustable longitudinally of the machine so as to have its relation with the underlying rollers 108 determined, such adjustment being secured by having the stem 5 of the brush mounted upon the bracket 130. The brush is adjustable transversely of the machine by having the bracket 130 slidably mounted upon the contiguous rod 124. The brush is also of service whether or not it 10 acts as a guide for the paper in that the sheet fed to the machine 1 will not buckle between the machine 1 and the brush.

The rollers 108 are all positively driven by a constantly operating sprocket chain 15 131, these rollers being turned in a counter-clockwise direction to feed the paper toward the machine 1. The rollers are forwardly inclined with respect to the guide portion 121 at their ends that are remote from said 20 guide whereby the edge of the paper being fed is maintained in engagement with the vertical portion 121 of the guide.

Before the paper reaches the brush 129 it is subject to frictional contact upon one side 25 thereof at the guide 120. Where narrower sheets are being fed this preponderating friction would be likely to throw the paper out of alinement by being retarded at the guide 120. I compensate, particularly where 30 narrow sheets are being fed, for the friction at 120 by supplying a friction device to lie upon and contact with the paper at the side thereof opposite the guide 120. This friction device may preferably be in the form 35 of a strip 132 depending from one of the frame rods 124 and extending forwardly longitudinally of the machine. By the equipment described the paper being fed is properly registered so as to make even contact 40 with the side guide portion 121 and drop guide 133.

The pump 45 is preferably common to the wind box 127, the suction pipes 48 and 56 and the fluffer 97, a single valve 134 throwing 45 the pump 45 into and out of service.

Certain features of my invention not herein claimed are claimed in my co-pending application Serial No. 831,363, filed April 13, 1914, which co-pending application is 50 a division of this application.

While I have herein shown and particularly described the preferred embodiment of my invention I do not wish to be limited to the precise details of construction shown as 55 changes may readily be made without departing from the spirit of my invention, but

Having thus described my invention I claim as new and desire to secure by Letters Patent the following:—

60 1. A sheet feeder including a suction shoe; a reciprocable support for the shoe upon

which it is pivotally mounted; a connection anchored at one end exteriorly of the shoe and at the other end attached to the shoe; mechanism for reciprocating said support 65 to effect oscillation of the shoe; and a spring for maintaining the aforesaid connection taut.

2. A sheet feeder including a suction shoe for lifting rear portions of the sheets; a support for positioning the rear portions of the sheets adjacent said shoe; a reciprocable support for the shoe upon which it is pivotally mounted; a connection anchored at one end exteriorly of the shoe and at the other end attached to the shoe; mechanism for reciprocating said support to effect oscillation of the shoe; and a spring for maintaining the aforesaid connection taut. 70 75

80 3. A sheet feeder including means for elevating portions of sheets that are to be fed from a pile of sheets; a finger in close proximity to the aforesaid means for resting upon the pile of sheets between the lifted sheet and the remaining sheets; and mechanism for moving said finger inwardly over the pile of sheets and downwardly after its inward movement has been finished to contact with the pile of sheets below the lifted sheet. 90

4. A sheet feeder including means for elevating portions of sheets that are to be fed from a pile of sheets; a finger for resting upon a pile of sheets between the lifted sheet and the remaining sheets, said finger 95 being in close proximity to the aforesaid means; and mechanism for moving said finger inwardly over the pile of sheets and downwardly after its inward movement has been finished to contact with the pile of 100 sheets below the lifted sheet and serving to lift the finger and withdraw it outwardly preparatory to another sheet lifting operation.

5. A sheet feeder including an oscillating 105 suction shoe for lifting sheet portions; and an abutment in the form of a leaf spring carried by and projecting endwise beyond the shoe and the outer end of which normally projects downwardly below the sheet engaging 110 face of the shoe and with which abutment sheets lifted by the shoe are brought into engagement to dislodge the sheets that are not to be lifted.

In witness whereof, I hereunto subscribe my name this eleventh day of September, A. D. 1913.

MICHAEL A. DROITCOUR.
